UNITED STATES PATENT OFFICE.

JACOB ATKINSON, OF PHILADELPHIA, PENNSYLVANIA.

STAMP-AFFIXING MACHINE.

SPECIFICATION forming part of Letters Patent No. 769,291, dated September 6, 1904.

Application filed April 27, 1903. Serial No. 154,513. (No model.)

To all whom it may concern:

Be it known that I, JACOB ATKINSON, a citizen of the United States, residing at Philadelphia, in the county of Philadelphia and State of Pennsylvania, have invented certain new and useful Improvements in Stamp-Affixing Machines; and I do declare the following to be a full, clear, and exact description of the invention, such as will enable others skilled in the art to which it appertains to make and use the same.

This invention relates to improvements in stamp-affixing machines.

The object of the invention is to provide a machine which will automatically feed and stick stamps upon envelops, means being provided for moistening the gum upon the stamps, provision being also made whereby the gum on the flap of the envelop may also be moistened, a further object being to provide a machine of this character which will be simple, strong, and practical, comparatively inexpensive of production, and well adapted to the use for which it is designed.

With these and other objects in view the invention consists in certain novel features of construction, combination, and arrangement of parts, as will be hereinafter more fully described, and particularly pointed out in the appended claims, reference being had to the accompanying drawings, in which—

Figure 1 is a side view of the machine. Fig. 2 is a longitudinal vertical sectional view. Fig. 3 is a side view of the machine with the casing removed. Fig. 4 is a vertical cross-sectional view on the line 4-4 of Fig. 2. Fig. 5 is a detail horizontal section through the plunger mechanism and knife on line 5-5 of Fig. 2. Fig. 6 is a detail vertical sectional view through the stamp-holder and lower end of the plunger mechanism, showing how the stamp is released and pressed on the envelop. Fig. 7 is a detail view of the means for releasing the stamp-reel.

In the drawings, 1 denotes the casing, which incloses the supporting-frame and operating mechanism.

2 denotes the base, upon which is mounted a suitable supporting-frame 3 comprising, two vertically-disposed parallel sides, each side

consisting of a main fixed plate 4, bolted or otherwise secured to the forward portion of the base, and a movable plate 5, hinged at its lower outer corner to the rearwardly-extending portion of the main fixed section 4. The 55 plates forming the two sides are suitably spaced apart and braced by cross-bars and shafts, as will be hereinafter described, the rear section of the frame formed by the plates 5 being adapted from its hinged connection to 60 swing rearwardly from the main section to permit access to the interior of the machine. The front and rear sections of the frame are locked in a closed position by means of spring-catches 6, fixed to the side plates 4 and adapted 65 to engage lugs 7, formed on the plates 5. A bail 8 is arranged above and spans the side plates, the lower ends of the bail being adapted to engage the spring-catches, so that when it is desired to release the same to open the frame 70 the bail is pressed downwardly, disengaging the catches from the lugs and allowing the plates 5 to swing back.

Between the side plates of the main fixed section of the frame is arranged a vertically-reciprocating carriage consisting of a pair of vertically-disposed plates 9, arranged between and fixed to the lower ends of which is a frame or box 10, in which is slidably mounted a head or block 12 and a pair of pivoted stamp-holding levers 13, each consisting of a plate pivoted at its upper end, having an inwardly-projecting lower edge or flange and an inwardly and upwardly projecting arm 14, formed on its upper end. The head or block 12 is provided with an upwardly-projecting beveled stud 12^a, which when the head 12 is forced downwardly is adapted to engage the arms 14 of the levers 13, thereby swinging the lower inwardly-projecting ends out from beneath 90 the block 12, the purpose of which will hereinafter appear. In the plates 9 are formed vertically-disposed slots 15, which are coincident with similarly-disposed slots 16, formed in the side plates 4, between which the plates 9 are adapted to slide.

17 denotes a vertically-reciprocating horizontally-disposed plate adapted to slide between the plates 9 and having formed on its sides adjacent to the said plates bearing flanges 100

or shoes 17^a. Projecting laterally from the plate 17 and passing through the slots 15 and 16, formed in the plates 9 and 4, are arms 18, on one of which is formed an upwardly-projecting slotted lug 19, in which is pivoted a hook 20, the bill of which projects inwardly. The construction of the hook and the lug 19 is such that the bill of the hook is allowed to swing downwardly and inwardly to enable it to pass any obstruction in its path of upward movement, but will engage obstructions in the path of its downward movement, the object of which will hereinafter appear. On the lower side of the plate 17 is formed a tapering plunger-head 21, and on the upper side of the plate is formed a slotted boss 22, to which is connected a ring 23, to which is attached the lower end of a strap 24, which is adapted to be wound upon a reel or pulley 25, mounted upon a shaft 26, rotatably mounted in the upper ends of the plates 4. On the shaft 26 is also mounted a spiral spring 25^a, one end of the same being connected to the said shaft and the opposite end being connected to the frame, the arrangement being such that as the strap 24 is unwound the shaft 26 will be rotated to wind up the spring, the tension of which will upon releasing the strap cause a retrograde movement of the shaft and reel 25 and wind up the strap again.

27 denotes a horizontally-reciprocating dog carried by the plate 17 and having a sliding engagement with the slot in the boss 22 formed on said plate. The rearwardly-projecting end of the dog 27 is beveled to form an engaging edge or point, while the forward end of the same is provided with a vertically-disposed opening 28.

29 denotes a vertically-disposed bar or rod 40 fixed at its upper and lower ends to cross rods or bars 30, connecting the side pieces 4 of the frame. The rod 29 is adapted to pass through the opening 28 in the dog 27 and is offset at its lower end, forming a bend and bringing the lower end of the bar in a plane in advance of the upper portion of the same.

On the sides of the box 10, carried by the plates 9, are laterally-projecting lugs 10^a, which are adapted to engage guide-slots 4^a, formed in the plate 4, whereby the plates 9 and box 10 are guided in their vertical movement.

31 denotes a transversely-arranged vertically-disposed plate fixed between the side plates 4, and in said plate is formed a horizontally-disposed feed slot or opening 32, which is arranged at the level of the lower end of the block 12, and in said plate is also formed a central vertically-disposed slot 33.

34 denotes a vertically-reciprocating plate, on the lower end of which is formed a knife 35. The plate 34 is adapted to slide upon the plate 31 and to be held in yielding engagement with the same by means of a bolt 36, fixed thereto and adapted to project through the slot 33.

On the end of the bolt 36 is screwed a nut, a spring 37 being coiled around the bolt between the said nut and the plate 31, whereby the plate 34 and knife-blade are held in close yielding engagement therewith. The upper end of the plate 34 is provided with a forwardly-projecting lug 38, and a similarly-arranged lug 39 is formed on the plate about midway between the upper and lower ends of the same, 70

40 denotes a stamp-reel upon which a web 75 or strip of stamps is adapted to be wound. A strip of waxed or oiled paper 40' is wound with the stamps, the paper serving to protect the stamps from the mucilage on the same, as will be understood. The reel 40 is removably 80 mounted in arms 41, projecting rearwardly from the plates 5, the end 41^a of one of said arms having a hinged connection with the main portion thereof, said end being held in engagement with the reel by means of a strong coiled 85 spring 42. The ends of the arms 41 are provided with inwardly-projecting pins, which are adapted to engage similarly-shaped depressions in the sides of the reel, whereby the reel is adapted to have a free rotary movement. 90

43, 44, and 45 denote horizontally-disposed rolls arranged across the frame and journaled in the plates 5, and between the rolls 43 and 44 is adapted to pass the strip of stamps, with its protective strip of waxed paper. After passing between the rolls the strip of stamps is directed into a flat metal guide tube or chute 46, while the strip of waxed paper is directed around the roll 43 and between the same and the roll 45, from which it is fed into a box or receptacle for this purpose. From the tube 46 the end of the stamp strip is directed beneath the head or block 12, where the end stamp is held by the pivoted levers 13. 95

47 denotes a spur-gear mounted upon the 105 shaft of the roll 43, and 48 denotes a similar gear fixed to shaft 49, rotatably mounted between the plates 5.

50 denotes a spur gear-pinion loosely mounted upon the shaft 49, and 51 denotes a ratchet-wheel fixed upon the shaft 49. A pivoted spring-pressed pawl 52 is carried by the gear 50, said pawl being in engagement with the teeth of ratchet-wheel 51, whereby when the gear 50 is rotated in one direction the pawl 52 110 will turn ratchet-wheel 51, shaft 49, and gear 48, which in turn will rotate the gear 47 and roll 43, which being in frictional contact with rolls 44 and 45 will cause them to be turned in proper direction. 115

53 denotes a lever pivoted to one of the side plates 4 of the frame, and on one end of said lever is formed a segmental rack 54, which is adapted to engage the teeth on the gear 50. The opposite end of the lever 53 is in the form 125 of an arm 55, the outer end of which is beveled or rounded off, as shown, and lies in the path of movement of and is adapted to be engaged by the pivoted hook 20, carried by one of the arms 18 on plate 17. 130

56 denotes a bail-shaped operating-lever having T-shaped inner ends. The lower branches of the T-shaped ends are connected to operating-bars 56^a, arranged on each side of the machine, the forward ends of which are pivotally connected to the ends of the arms 18 of the plate 17. The opposite ends of the bars 56^a are provided with longitudinally-disposed slots 56^b, which are adapted to have sliding engagement with studs 56^c, projecting from the side plates of the machine, as shown.

57 denotes curved arms or braces, one end of each of which is pivotally connected to a stud 56^c, and the opposite end is connected to the upper branch of one of the T-shaped ends of the operating-lever.

57' denotes a knob or finger-piece fixed in the forwardly-projecting loop of the operating-lever 56.

20 In the forward portion of the base of the machine is formed a concavity 58, in which is adapted to slide a bed piece or block 59, having an outwardly and downwardly curved flange or lip 60. The block 59 is supported 25 in the concavity 58 and normally held above the base by means of stiff coiled springs 61, arranged beneath the block, as shown.

62 denotes a water-tank arranged upon the front edges of the side plates of the frame, and 30 in the contracted lower end of the same is arranged a strip of felt or other absorbent material 63, the same being in contact with the water in the tank.

64 denotes a filling-opening arranged in 35 the upper end of the tank and normally closed by a cap or stopper.

65 denotes a roller rotatably mounted in a pivoted bail 66, carried by the tank 62.

The lower ends of the forward portion of 40 the plates 4 are cut away to form slots 67 above the base and block 59, whereby an envelop may be inserted below the same and onto the block 59, the springs beneath said block allowing the same to be pressed down 45 to accommodate bulky envelops or small packages. The front portion of the casing ends above the base for the insertion of the envelops, as herein described.

68 denotes a regulating-screw mounted in 50 a lug 69, projecting from one of the plates 4 above the arm 55 of the segmental lever 53, whereby upon lengthening or shortening the ends of the screw the stroke of the lever 53 is regulated or adjusted, which will cause the feed-rolls to be turned more or less, according 55 to the size of the stamps used.

The operation is as follows: The envelop to be stamped is inserted in the slots 67 and upon the bed or block 59, and when inserting the 60 envelop the face of the same is brought into engagement with the wet felt strip 63 beneath the water-tank and by which a wet place is formed on the envelop which, when the same is pushed entirely in will lie imme-

diately below the reciprocating carriage carrying the stamp. The operating-lever is now pressed, forcing down the arms 18 on plate 17, one of which carries the hook 20, which catches or engages with the arm 55 on the lever 53. Further downward movement of the 70 operating-lever causes the segmental rack 54, formed on the opposite end of the lever 53, to rotate the pinion 50, which actuates the train of gears as hereinbefore described to turn the rolls and feed the stamps from the 75 reel through the tube until one stamp lies beneath the block or head of the carriage, where it is held in position by the pivoted levers carried thereby. When the stamp strip reaches this position, the hook 20 will have reached 80 the rounded end of the arm 55 and slides from engagement with the same. Further downward movement of the operating-lever brings the point of the dog 27 into engagement with the lug 39 on the knife-plate and forces the 85 same downwardly, causing the knife to sever the stamp from the strip, at which time the offset lower portion of the bar 29 causes the dog to retract from engagement with the knife-plate. Further downward movement 90 of the lever brings the plate 17 into engagement with the stamp-holding box or frame 10 and forces the same downwardly. At the same time the plunger-head 21 engages the beveled stud 12^a on the plate 12 and forces 95 the same down, simultaneously opening the levers 13 and allowing the stamp to drop upon the wet portion of the envelop, the head or block 12 descending upon the same and pressing it in place, when upon releasing the operating-lever the envelop may be withdrawn 100 from the bed or block, and in passing beneath the roller 65 it is further rolled and pressed upon the envelop, the roller also serving to protect the stamp from the wet felt as the envelop is drawn out. This action of the roller results from the fact that it is relatively fixed and its lower side is lower than the wet felt of the moistening device, so that the roller acts as a stop to limit the movement of the 105 block 56, carried by the springs 61 toward the wet felt, and keep the blocks from contacting with the felt and from forcing the stamp against the felt. When the operating-lever is released, the spring 25^a, which has 110 been wound upon the shaft 26 by the downward movement of the parts, will unwind, causing a retrograde movement of the shaft 26 and reel 25, winding up the strap 24 and returning the plate 17 and its attached parts to 115 their normal positions, the upward movement of these parts engaging the lug 38 on the knife-plate and the segmental and operating levers and restoring them to their normal positions, as will be understood.

The pawl-and-ratchet connection between the loose gear-pinion 50 and the shaft 49 permits the segmental rack to turn back to its 120

normal position without causing a retrograde movement of the shaft 49 and the parts driven thereby.

The gummed edge of the envelop-flap may be passed under the strip of felt connected to the water-tank, and thereby moistened for sealing.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of this invention.

Having thus fully described my invention, what I claim as new, and desire to secure by Letters Patent, is—

1. The combination of a strip-feeder, a lever, connections operated by the initial movement thereof to actuate the strip-feeder, a plunger actuated by the lever at a later period of the movement thereof, a movable cutter operated by the plunger, to sever a section from the strip, laterally-movable means to support the strip-section, and a strip-section affixer subsequently operated by the plunger during the same movement thereof, to release the strip-section-supporting means therefrom and affix the strip-section.

2. In a machine of the class described, the combination of a spring-supported supporting element, a relatively fixed moistener opposed thereto, and a roller having a relatively fixed axis, disposed in rear of the moistener, bearing on the supporting element and forming a stop to prevent the latter from contacting with the moistener.

3. The combination of a strip-feeder, a lever, connections operated by the initial movement thereof to actuate the strip-feeder, a plunger actuated by the lever at a later period of the movement thereof, a cutter operated by the plunger to sever a section from the strip, a strip-section affixer subsequently operated by the plunger during the same movement thereof, a spring to reversely move the plunger when the lever is released, and connections actuated by the reverse movement of the plunger to restore the lever, the cutter and the affixer to their initial positions.

4. In a device of the character described, and in combination with mechanism for feeding a strip of stamps, a reciprocating stamp-applyng device, a cutter for severing the individual stamps from the strips, a stamp-engaging device carried by the applying device, a movable member adapted to first actuate the stamp-feeding mechanism, then to actuate the cutter to sever a stamp and then operate the stamp-engaging device to release the stamp as the stamp-applying device moves into ap- 65 plying position, substantially as described.

5. In a machine of the character described, the combination with a supporting-frame, of a vertically-reciprocating carriage and stamp-holder and a vertically-reciprocating knife or cutter, means for reciprocating said carriage and stamp-holder, and means for engaging and reciprocating said cutter, a stamp-reel rotatably mounted in said frame and having wound thereon a strip of stamps, feed-rolls adapted to unwind and feed said strip of stamps from said reel to said holder, means for rotating said rolls, and a moistening device adapted to impart moisture to an envelop to cause a stamp to stick thereto, substantially as described.

6. In a machine of the character described, the combination with a supporting-frame, of a vertically-reciprocating carriage and stamp-holder, a vertically-reciprocating knife or cutter, a reciprocating plate having laterally-projecting guide-arms and a depending plunger-head, adapted to engage and reciprocate said carriage and stamp-holder, automatically-operated means carried by said plate for engaging and reciprocating said knife or cutter, and means for reciprocating said plate, a stamp-reel rotatably mounted in said frame, and having wound thereon a strip of stamps, feed-rolls adapted to unwind and feed the stamps from said reel to said stamp-holder, a train of gears adapted to drive said rolls, means for actuating said train of gears to turn said rolls in one direction, means to prevent retrograde movement of said rolls, and a moistening device supported by said frame, substantially as described.

7. In a machine of the class described, the combination with a supporting-frame, of a vertically-reciprocating carriage and stamp-holder, a vertically-reciprocating knife or cutter, a reciprocating blade having laterally-projecting guide-arms and a depending plunger-head, adapted to engage and reciprocate said carriage and stamp-holder, a sliding dog carried by said plate and adapted to engage and reciprocate said knife or cutter, means for automatically disengaging said dog from said cutter, a pivoted operating-lever adapted to engage said guide-arms to project said plate, and means for automatically retracting said plate, and restoring said carriage and stamp-holder and said cutter to their normal position, a stamp-reel rotatably mounted in said frame and having wound thereon a strip of stamps, feed-rolls adapted to unwind and feed said stamps from said reel to said holder, a train of gears adapted to drive said rolls, a segmental lever adapted to actuate said gears to drive said rolls in one direction, and a clutch device for preventing a retrograde movement of said rolls, and means operating said segmental lever, substantially as described.

8. In a machine of the character described, the combination with a supporting-frame, of a vertically-reciprocating carriage and stamp-

holder, a vertically-reciprocating knife or cutter, a reciprocating plate having laterally-projecting guide-arms and a depending plunger-head, adapted to engage and reciprocate said carriage and stamp-holder, a sliding dog carried by said plate and adapted to engage and reciprocate said knife or cutter, a curved rod or bar adapted to be engaged by said sliding dog, to disengage the same from said cutter, a pivoted operating-lever adapted to engage said guide-arms to project said plate, a pulley fixed to a shaft and having wound thereon a strap, one end of which is fixed to said plate, a spiral spring mounted on said shaft and adapted to be wound up as said shaft is unwound by the movement of said plate, whereby upon release of pressure upon said plate, said spring will unwind thereby rewinding said strap and retracting said plate which will restore said carriage and stamp-holder to their normal position, a stamp-reel rotatably mounted in said frame and having wound thereon a strip of stamps, feed-rolls adapted to unwind and feed said stamp from said reel

to said holder, a train of gears adapted to drive 25 said rolls, a segmental lever adapted to actuate said gears to drive said rolls in one direction, and a clutch device for preventing a retrograde movement of said rolls, a pivoted hook carried by one of the guide-arms of said 30 reciprocating plate, and adapted to engage and operate said segmental lever, and means for regulating the movement of said lever, substantially as described.

9. In a machine of the class described, the 35 combination of a spring-supported supporting element, a moistener opposed thereto and a roller opposed to said supporting element and preventing the moistener from coming in contact therewith.

In testimony whereof I have hereunto set my hand in presence of two subscribing witnesses.

JACOB ATKINSON.
